Specification of Letters Patent.

Patented Jan. 2, 1917.

Application filed October 2, 1915. Serial No. 53,750.

To all whom it may concern:

Be it known that we, JOHN F. OHMER and HARRY J. SIBLEY, citizens of the United States, residing at Dayton, in the county of 5 Montgomery and State of Ohio, have invented certain new and useful Improvements in Transfer Printing and Issuing Machines; and we do declare the following to be a full, clear, and exact description of the 10 invention, such as will enable others skilled in the art to which it appertains to make and use the same, reference being had to the accompanying drawings, and to the letters and figures of reference marked thereon, 15 which form a part of this specification.

This invention relates to new and useful improvements in machines for extemporaneously printing and issuing transfers such as are used on street railway lines to 20 enable passengers to transfer from one car line to another.

The present invention is an improvement of the mechanism shown and described in the co-pending application filed January 11, 25 1915, Serial No. 1606.

An object of the invention is to provide a new and improved form of impression mechanism whereby a more legible and perfect printing of the transfers ensues.

30 A further object of the invention is to provide improved means for locking the machine against operation.

A further object of the invention is to provide means for locking the movable type, 35 from which is printed the changeable data, during the printing operation therefrom.

A further object is to provide an improved form of paper cutting means which effectually severs the paper from the ticket or 40 transfer strip after each printing operation.

A further object is to provide a new and improved form of dash pot that controls the 45 operation of the mechanism and prevents it being operated too quickly.

50 A further object is to provide means for firmly attaching the machine to a supporting column in a manner that enables it to be easily detached therefrom. And a still further object of the invention is to provide a machine of the above character for printing all the necessary data on transfers, including indications denoting the lines from which and to which each transfer is issued.

Referring to the accompanying drawings,

Figure 1 is a front elevation of the machine 55 including the supporting column; Fig. 2 is a front elevation of the machine with the casing shown in section; Fig. 3 is a section approximately on the line 3—3 of Fig. 2; Fig. 4 is a section approximately on the line 4—4 60 of Fig. 2; Fig. 5 is a view of the right side of the machine as viewed from Fig. 1 with the casing removed; Fig. 6 is a view of the left side of the machine with the casing removed; Fig. 7 is a sectional elevation approximately on the line 7—7 of Fig. 2; Fig. 8 is a sectional view of the supporting column approximately on the line 8—8 of Fig. 1 showing the location of the dash pot; Fig. 9 is a section of the column approximately 70 on the line 9—9 of Fig. 8; Fig. 10 is a view of the indicating plate by means of which the various movable type are set or indexed; Fig. 11 is a perspective view of the identification key; Fig. 12 is a view of the locking member controlled by the identification key; Figs. 13 and 14 are detail diagrammatic views of the means for shifting the platen during the printing operations; Fig. 15 is a detail sectional view of the paper 80 carrying roll; and Fig. 16 is a view of the printed ticket or transfer.

Throughout the specification and drawings, similar reference characters indicate corresponding parts both in the description 85 and drawings.

Referring more particularly to the drawings, 1 (Fig. 1) represents a floor plate having a suitable boss 2 which receives the lower end of a supporting column 3. The upper end 90 of said column 3 is adapted to receive a suitable boss 4 on the under side of a base plate 5 upon which the machine is supported and which machine is constructed as follows:— The machine is provided with a frame work 95 consisting of side plates 6 and 7 connected by a frame 8 in which the impression or printing wheels are mounted, and by a plate 9 upon which the paper severing means is mounted. At the right hand end, as seen from Fig. 2, the frame 8 is provided with type wheels 10 which are manually set through the aid of gears 11 and drums 12 (Figs. 2, 4 and 7). The type wheels 10 are adapted to print the day upon which each transfer is issued, as 105 will be seen in Fig. 16. To the left of the type wheels 10 is a consecutive number printing counter 13 which is actuated from

a lever 14, hereinafter referred to (Figs. 4 and 7). This counter 13 prints the serial number upon the transfer and is instrumental in indicating the number of transfers issued by the machine. To the left of the counter 13 is a type wheel 15 adapted to print the ante-meridian or post-meridian indications upon the transfer. This wheel is also adapted to print half fare or other classified indications on the transfer. To the left of the wheel 15 is a wheel 16 and a wheel 17, said last named wheels being adapted to print the minute and hour of the day when the transfer was issued. To the left of the wheel 17 is a wheel 18 which is instrumental in printing the direction of travel. The wheels 15, 16, 17, and 18 are provided with pinions 19 (Figs. 3 and 7) which mesh with segment gears 20 mounted upon a shaft 21. The segment gears 20 are provided with extensions 22 which extend through suitable slots 23 (Fig. 1) in the casing 24. The extensions 22 may be shifted to rock the type wheels to select any desired printing matter thereon.

To indicate what type is in a printing position, a plate 25 is mounted upon the casing 24 which contains suitable visual indications along the slots 23 (Fig. 10). The above type wheels are mounted upon a shaft 26 secured in the frame 8 (Fig. 7). To the left of the type wheel 18 are type wheels 27 and 28 which are adapted to print the names of the various divisions of street rail-way lines. One printed indication is for the line issuing the transfer, while the other indication is for the line to which the transfer is issued (Figs. 2, 3 and 7). The type wheels 27 and 28 are mounted upon the shaft 21 and are provided with pinions 29 which mesh with segment gears 30 mounted upon levers 31 pivoted at 32 to the frame 8. The levers 31 are provided with extensions 33 which extend out through suitable slots 34 (Figs. 1 and 10) and which may be moved in connection with suitable indications on the plate 25 to place the type of the selected car line in printing position within the machine. Mounted below the type wheels above described and upon the frame 8 is a stationary plate 35 (Figs. 2 and 3) which is adapted to print on the transfer the name of the company and the conditions under which the transfer is issued and is to be used. Also an identification key 36 (Figs. 2, 5, 7 and 11) is adapted to print on the transfer. The said identification key when in printing position is mounted in a housing 37 attached to the side plate 7. In addition to printing on the transfer, the key 36 is adapted to unlock and lock the machine against operation, as will be hereinafter described.

Mounted between the side frames 6 and 7 is a paper roll carrying spool constructed

as follows (Figs. 3, 6 and 15). The said spool consists of a central sleeve 38 and ends 39 and 40. The central sleeve is adapted to receive spindles 41 and 42 which are journaled respectively in the side plates 6 and 7. Mounted within the sleeve 38 and between the spindles 41 and 42 is a spring 43 which holds said spindles in their bearings and permits the spindle 42 to be moved inwardly to allow the spool as a whole to be removed from the machine. The spindle 42 is provided with a disk 44 having a recess 45 the edge of which, when the spring 43 is compressed, is adapted to enter a recess 46 in a pin 47 mounted on the end 40, thereby allowing the spool to be removed in an assembled condition. The spool is removed from the machine in order to place a new roll of paper thereon. To indicate the amount of paper upon the spool at any time, the following indicating device is provided (Figs. 5 and 15). Pivoted at 48 to the side plate 7 is a lever 49 one end of which is provided with a roller 50 which is maintained by gravity upon the periphery of the roll of paper. The other end 51 of the lever 49 is adapted to indicate through a suitable slot (not shown) in the casing the position of the roller 50 relative to the center of the spool and, consequently, the amount of paper upon the spool.

The web of paper 52 as it unwinds from the spool passes upwardly between the printing type and a roller platen 53 which is part of the impression mechanism, said impression mechanism being constructed as follows (Figs. 2 and 3). The roller platen 53 is mounted upon a shaft 54 journaled in swinging end plates 55 pivoted on a shaft 56. Said shaft 56 is mounted in adjustable bearings 57 which are supported by screws 58 mounted in bosses 59 which are a part of a vertically movable frame 60. Said frame 60 is provided with projections 61 having upper and lower rollers 62 which ride in races 63 in guides 64 attached to the inner side of the side plates 6 and 7. The frame 60 is moved vertically by actuating means hereinafter described. The roller platen 53 is provided with a gear 65 (Figs. 7 and 13) which meshes with a rack 66 mounted in the frame 8. The rack and gear compel the platen to rotate over the face of the type. When the platen 53 rolls over the face of the type, it presses the paper web 52 against the same thereby securing an impression. The type are previously inked by a felt roller 67 which is mounted upon a shaft 68 journaled in side plates 69 pivoted on the shaft 54. Attached to the plates 69 are springs 70 which press the roller 67 against the type when inking the same. When in the normal position, the roller 67 lies adjacent to an ink well 71 mounted upon the frame 8 (Fig. 3). The ink roll 67 is pro-

vided with a guard 72 which prevents the paper strip 52 coming in contact with the inking roll. When the platen roll 53 has reached the end of its upward movement and has made a complete impression upon the web 52, the said roll is disengaged from the type by pins 73 mounted in the races 63 and adapted to engage the upper rollers 62, thereby shifting the frame 60 and the roller 58 carried thereby.

During the downward movement of the platen, the said platen is held away from the type to prevent the securing of a second impression and to allow the paper to be fed by the following means: As before stated, the platen 53 is mounted upon end plates 55 pivoted on the shaft 56. This arrangement allows the platen to swing upwardly and away from the type. During the downward movement of the platen, one of the plates 55 engages the upper end of a latch 74 (Figs. 2, 7, 13 and 14) and trips said side plate to a position shown in Fig. 14, it being understood that both end plates 55 are rigidly attached to the shaft 56. When in the position shown in Fig. 14, the roller platen 53 rides away from the type and allows the paper strips to be fed forward unobstructed. The latch 74 which is under the control of a spring 75 is pivoted at 76 in the frame 8. When the platen reaches the lower end of its descending movement, the latch 74 releases the end plate 55 thereby enabling the platen to assume its normal position or that shown in dotted lines in Fig. 13. It will be noted from Fig. 14 that during the downward movement of the platen the gear 65 and the rack 66 were not completely unmeshed thereby permitting the rack to rotate the platen during the subsequent printing operation. After an impression has been secured, the paper is fed forward by the following means: The paper strip 52 passes upwardly between upper feed rollers 77 and lower feed rollers 78. The upper rollers 77, which are the pressure rollers, are mounted upon a shaft 79 journaled in the ends of slides 80 mounted in guides 81 and controlled by springs 82 (Figs. 2 and 3). The lower rollers 78, which are the actuating rollers, are mounted upon a shaft 83 journaled in the side plates 6 and 7. The left end of the shaft 83 is provided with a pinion 84 (Figs. 2 and 6) which meshes with a gear 85 mounted upon a shaft 86 journaled in a frame 87 attached to the side plate 6. The gear 85 carries a pawl 88 adapted to be engaged by a ratchet 89 mounted upon the shaft 86 and rigidly secured to a pinion 90. Said pinion 90 is provided with a flat face 91 which is engaged by the edge of a sliding member 92 and locks the printing rolls against rotation. The sliding member 92 is provided with a rack 93 adapted to mesh with the

pinion 90. It is mounted in a guide formed by the side plate 6 and frame 8 (Fig. 7) and is actuated from the frame 60 of the printing mechanism. Mounted upon the frame 60 is a projection 94 (Fig. 6) adapted to engage the upper and lower ends of a recess 95 in the lower end of the sliding member 92. The arrangement of the ratchet 89 is such that the feeding rollers will be actuated at the end of the downward movement of the frame 60 and platen 53. When the frame 60 reaches the end of its downward movement, the paper is severed by the following means: Slidably mounted upon the plate 9 and within the guides 81 is a knife 96 which cooperates with the edge 97 of an opening 98 in the plate 9 through which the paper strip passes (Fig. 3). The knife 96 is pulled downwardly by means of springs 99 which are attached to suitable studs 100 secured to the knife and to a cross-plate 101. The knife 96 is elevated by a crank 102 mounted on a shaft 103 journaled in bearings 104 attached to the plate 9 (Fig. 4). One end of the shaft 103 is provided with a crank 105 adapted to be engaged directly by a vertical projection 106 when the frame 60 is in its elevated position. When thus elevated, the said knife 96 is held in an elevated position by a latch 107 pivoted on the shaft 26 adapted to engage the end 108 of the crank 105. The latch 107 is provided with an elongated extension 109 the lower end of which is adapted to be engaged by a stud 110 on a bracket 111 extending from the frame 60. When said frame 60 reaches its lowermost position, the stud 110 engages the extension 109 which operation rocks the latch 107 and releases the knife 96 thereby enabling the springs 99 to actuate the knife to sever the paper. When thus severed, the transfer made from the severed portion of the paper strip is held by the cross-plate 101 and a clamping plate 112. The clamping plate 112 is movable in the guides 81 and is controlled by springs 113 and the crank 102, it being elevated simultaneously with the knife. When the paper strip is fed by the feed rollers 77 and 78, it is fed into a pocket 114 (Fig. 3) which extends out through the casing and thus enables the transfer to be grasped by the passenger.

To separate the feed rollers 77 and 78 so that the paper strip may be inserted, the slides 80 are provided with projections 115 adapted to be engaged by the upper edge of the knife 96 during an extended elevated movement which is imparted to the knife through the crank 105 and a lever 116 (Fig. 5). Said lever 116 is pivoted at 117 to the side frame 7 and one end thereof is adapted to engage the end 108 of the crank 105. The other end of the lever 116 is adapted to be elevated by a sliding member 118 mounted

in bearings 119 on the inner side of the plate 7. The lower end of the sliding member 118 is adapted to be engaged by a manually actuated cam 120 pivoted on a cross-rod 121. When the cam 120 is moved upwardly, the knife 96 and the clamping plate 112 will be elevated and the feed rollers 77 and 78 will be separated. The slides 80 are provided with springs 82 which are instrumental in forcing the feed rollers together thereby causing them to properly grip the paper during the feeding operation.

The frame 60 is prevented from being elevated and the machine is locked against operation when the key is extracted as follows:—The vertical projection 106 is provided with a shoulder 123 (Fig. 4) adapted to be engaged by an edge 124 of a swinging locking member 125. Said locking member 125 (Fig. 12) is pivoted at 126 and is provided with a spring 127 which tends to move it to a locking position with the edge 124 in engagement with the shoulder 123. The said locking member 125 is provided with a cam slot 128 adapted to receive a pin 129 on the under side of the key 36. When the key is inserted the pin 129 will rock the locking member 125 to the position shown in Fig. 4, thereby elevating the frame 60. However, when the locking member 125 is in a locking position, the said member itself is held in a locking position against accidental displacement by a latch 130 (Fig. 5) pivoted at 131 and influenced by a spring 132. The latch 130 is provided with an end 133 adapted to engage or lie in the path of a projection 134 of the locking member 125 when said locking member is in a locking position. The latch 130 is provided with a projection 135 which enters a recess 136 (Fig. 7) in the key housing 37. The latch 130 is adapted to be elevated by a cam 138 (Fig. 11) on the key 36 when said key is inserted. Therefore, to unlock the machine it is necessary to first elevate the latch 130 and then rock the locking member 125 which operations are consecutively performed when the key is inserted. When the key is withdrawn, the operations are performed in a reverse order thereby locking the machine against operation.

To prevent the type wheels 15, 16, 17, 18, 27 and 28 from being set during the time the frame 60 is elevated and the printing operation is performed the following means are provided:—The segment gears 20 (Fig. 3) are provided with star-ratchets 139 in operative relation with levers 140 pivoted at 141 and provided with extensions 142 and 143 under the influence of springs 143. The type wheels 27 and 28 are provided with star-ratchets 144 in operative relation with levers 145 pivoted at 32. The levers 145 are under the influence of springs 146 and are provided with projections 147, which enter

the recesses in said ratchets. The levers 140 and 145 together with the ratchets 139 and 144 are instrumental in assisting the operator when placing the type in a printing position during the selecting or setting operations. The said levers hold the type wheels in their printing positions during the printing operation and are instrumental in locking the type wheels by the following means:—The extensions 142 of levers 140 and projections 148 of levers 145 are adapted to be engaged by or to lie in the path of arms 149 and 150 mounted upon a shaft 151 journaled in the frame 8. When the frame 60 is in its lowermost position, the projections 142 and 148 lie outside of the path of the arms 149 and 150 thereby allowing the levers 140 and the extensions 147 to ride in and out of the teeth of the star-ratchets 139 and 144 thus setting the wheels. When the frame 60 is elevated the arms 149 and 150 move into the path of the projections 142 and 148 thereby locking the type wheels. The arms 149 and 150 are thus moved by rocking the shaft 151. The shaft 151 is provided with a slotted cam lever 152 which is in operative relation with a pin 153 carried by the bracket 111 on the frame 60. When the frame 60 is initially elevated it will be seen that the shaft 151 will be rocked, thereby moving the arms 149 and 150 into the path of the projections 142 and 148 and locking the type wheels in a printed position.

During the descending operation of the frame 60, the consecutive numbering counter 13 is actuated through the following means: The pin 153 on the bracket 111 rides in a slot 183 of less length than the stroke of the frame 60. The slot 183 is in the lower end of a member 184 pivoted at 185 to a lever 186. Said lever 186 is connected to the lever 14 of the counter 13 by a link 187. When the frame 60 is elevated, the pin 153 strikes the upper end of the slot 183 thereby rocking the lever 186 and depressing the lever 14. At the end of the downward movement of the frame 60, the pin 153 strikes the bottom of the slot 183 and thereby elevates the lever 14 and actuates the consecutive numbering counter 13. To compel the printing mechanism to make a complete vertical and horizontal movement, a full stroke mechanism is provided which consists of a pawl 154 (Fig. 4) pivoted at 155 to the frame 60 and controlled by a spring 156. The pawl 154 operates in connection with a star-rack 157 mounted on the frame 8 in a well known manner.

The machine proper is inclosed in a casting 24 which is provided with doors 158 and 159 for access to the interior of the machine when placing a new roll of paper therein.

The machine is actuated from a foot treadle 160 (Fig. 1) mounted in the floor 130

plate 1. Said treadle is connected to the frame 60 through connecting means which extends through the column 3 and is constructed as follows (Figs. 8 and 9.) Pivotally attached to the treadle 160 are two bars 161 which are attached to the lower end of a dash pot 162. The upper end of said dash pot is connected to bars 163 which are in turn connected to a bar 164. Said bar 164 is slidably mounted in a guide 165 and is provided with a projection 166 adapted to engage the projection 167 (Fig. 3) extending from the lower portion of the frame 60. The dash pot 162 is provided with a piston 168 attached to the lower end of a piston rod 169. The upper end of the piston rod 169 is slidably mounted on a horizontal pin 170 mounted in the column 3. The dash-pot 162 is provided with a suitable quantity of oil which prevents the treadle 160 being actuated too quickly. The frame 60 and the connection between the frame and the treadle 160 is moved downwardly to a normal position by springs 171 attached to the lower end of the dash pot 162 and to the column 3.

The machine proper, including the base plate 5, may be detached and removed from the column 3 as follows:—The said base plate 5 is provided with the boss 4 which receives the upper end of the column 3. The machine is locked upon the upper end of the column 3 by a sliding bolt 173 provided with an opening which receives the bar 164. The bolt 173 is mounted in the boss 4 and is actuated by a bell-crank lever 174 pivoted at 175 in flanges 176 which extend from the boss 4. The bolt 173 is provided with projections 180 adapted to engage a shoulder 181 of T-slots 182 in the upper end of the column 3, thereby locking the machine on the column. When the bolt 173 is in a locking position, it is locked in this position by the pin 177 mounted in the flanges 176 and lying in the path of the bell-crank lever 174. When the pin 177 is removed and the handle portion of the bell-crank lever 174 is elevated, the bolt 173 is moved to a position to allow the boss 4 to be slid off of the end of the column 3. At the same time, the projection 166 on the upper end of the bar 164 is detached from the projection 167 on the lower side of the frame 60, thereby completely detaching the machine from the column 3. When the projection 166 is disengaged from the projection 167, the bar 164 is held in its shifted position by a spring-controlled plunger 178 in the guide 165, and when in this position, the connecting means between the treadle and the machine proper is locked by the pin 179 in a position to engage the guide 165 when the treadle 160 is actuated, thereby preventing tampering when the machine is removed from the column.

Mode of operation: The machine proper is placed on the column 3 by shifting the lever 174 to a position with the projections 180 out of the path of the upper end of the column 3. The boss 4 is then slid upon the upper end of the column 3 and the lever 174 is moved to the position shown in Fig. 3 where the projections 180 will engage the shoulders 181 thereby locking the machine on the column. At the same time the projection 166 is placed in operative relation with the projection 167 thereby connecting the treadle 160 with the frame 60. If not previously accomplished, the roll of paper is placed upon the spool and the spool is placed in proper position, which is shown in Fig. 3. The web of paper is then threaded between the platen 53 and the guard 72 and is extended between the feed rollers 77 and 78 where the end is in a position to be fed through the pocket 114. The date wheels 10 are then set by rotating the drums 12. The machine is then in a condition to be taken in charge by the conductor who then inserts his identification key 36 in the housing 37. When the identification key is inserted, the cam 138 thereon elevates the latch 130 which disengages the end 133 from the projection 134 of the locking member 125. During the extended movement of the insertion of the identification key, the pin 129 on the key will engage the cam slot 128 thereby shifting the locking member 125 and moving the edge 124 out of the path of the shoulder 123 of the vertical projection 106, thereby unlocking the impression mechanism. When the conductor desires to issue a transfer, he selects the time and direction by moving the extensions 22 and selects the car lines from which and to which the transfer is issued by shifting the extensions 33. This operation rotates the type wheels 15, 16, 17, 18, 27 and 28 and moves the selected printing type thereon to a printing position. The machine is then in a condition to issue a transfer which is accomplished by pressing down by the foot on the treadle 160. When the treadle 160 is moved downwardly, the bars 161, the dash pot 162, and the bars 163 and 164, are moved upwardly which elevates the platen carrying frame 60 through the agency of the projections 166 and 167. During this operation, the movement is retarded by the oil in the dash pot 162 in a well known manner. During the upward movement of the frame 60, the inking roll 67 and the platen roll 53 are moved over the face of the type which secures an impression on the web 52 thereby printing a transfer. During the initial downward movement of the frame 60, one of the end plates 55 which carries the platen 53 is tripped by the latch 74 which holds the platen away from the type thereby eliminating the possibility of securing a second impression.

When the frame 60 reaches the end of its upward movement, the vertical projection 106 strikes the crank 105 which locks the shaft 103 and elevates the knife 96 and the clamping plate 112, thereby permitting of the subsequent feeding of the paper web through the pocket 114. The knife and clamping plate are held in this elevated position by a latch 107 which engages the end 108 of the crank 105. During the downward movement of the platen, the projection 94 carried by the frame 60 engages the lower end of a recess 95 in the sliding member 92 which rotates the pinion 90, ratchet 89, gears 85 and 84, and the feed rollers 77 and 78, thereby feeding the paper. When the frame 60 reaches the lowermost end of its downward movement, the stud 110 will strike the extension 109 of the latch 107 thereby releasing the knife 96 and clamping plate 112 and enabling the springs 99 and 113 to sever and to hold the completed transfer. Also, during the downward movement of the frame 60, the consecutive number counter 13 is actuated through the member 184, lever 186, link 187, and the lever 14. During the time that the platen was in its ascending and descending movements, the type wheels 15, 16, 17, 18, 27 and 28 were locked in their set positions through the agency of arms 149 and 150 which are adapted to lie in the path of the projections 142 and 148 on the levers 140 and 145, the levers 140 and 145 being in operative relation with the star-ratchets 139 and 144. The arms 149 and 150 are mounted on the shaft 151 as before stated and are rocked through the agency of the pin 153 which engages the cam lever 152, also mounted on the shaft 151.

Having described our invention, we claim:

1. In a machine of the type specified, a printing type, a platen mounted on tilting members and adapted to move over the face of said type, and a latch adapted to engage one of said tilting members to move said platen away from the type and to hold it away from the type during its descending movement through the continued engagement between said latch and said tilting member.

2. In a machine of the type specified, a printing type, a roller platen mounted on tilting members and adapted to move over the face of said type, and a spring-controlled pivotal member adapted to engage one of said tilting members to move the platen away from the type and to hold said platen away from said type during its descending movement, through the continued engagement between said pivotal and said tilting member.

3. In a machine of the type specified, a printing type, a reciprocable frame, a pivotal frame mounted on said reciprocable frame, a roller platen mounted on said pivotal

frame and adapted to move over the face of said type during its ascending movement, and a latch pivoted in the path of the descending movement of said pivotal frame and adapted to engage one end of said pivotal frame to move said platen away from said type and to hold it in such position during its descending movement, through the continued engagement between said latch and the end of said pivotal frame.

4. In a machine of the type specified, the combination of printing members, a roller platen, means for imparting a reciprocable and rotary movement to said platen, tilting frame members 55 in which said roller platen is journaled, and a pivotal member 74 arranged in the path of one of said members 55 and adapted to engage said member 55 during the descending movement of the platen to move and hold said platen away from the type during such descending movement through a direct engagement between said pivotal member 74 and said frame member 55.

5. In a machine of the type specified, a printing type, a roller platen adapted to move over the face of said type, a rack and pinion adapted to rotate said platen, an oscillating frame for said platen comprising end plates 55 and connecting shaft 56, and a spring-controlled pivotal latch adapted to engage one end of said frame to move said platen and to hold it out of a printing position during its descending movement.

6. In a machine of the type specified, a printing type, a reciprocable frame, a pivotal frame mounted in said reciprocable frame, a roller platen mounted in said pivotal frame and adapted to move over the face of said type, a rack and pinion adapted to rotate said platen, a spring-controlled pivotal latch adapted to move and to hold said platen out of a printing position during its descending movement, said frame being in engagement with said latch during the descending movement of the platen.

7. In a machine of the type specified, a printing wheel, means for indexing the same to printing positions, means for locking said printing wheel when moved to a printing position including a ratchet and a co-operating lever, printing mechanism co-operating with said wheel including a platen and a reciprocable frame carrying said platen, means actuated by said reciprocable frame co-operating with said locking means and including an arm mounted on a shaft and adapted to engage said co-operating lever when the reciprocable frame is elevated to lock said printing wheel, and a cam lever actuating said shaft from said reciprocable frame.

8. In a machine of the type specified, a printing wheel, means for indexing the same to printing positions, means for locking said

printing wheel when moved to a printing position including a ratchet 144 and lever 145, printing mechanism coöperating with said wheel including a platen 53 and a reciprocable frame 60 carrying said platen, and means actuated by said reciprocable frame and coöperating with said locking means including an arm 150 mounted on shaft 151 and adapted to engage said lever 145 when the reciprocable frame is elevated, and cam lever 152 actuated from said reciprocable frame to rock said shaft 151 and thereby move the arm 150 into the path of the lever 145.

9. In a machine of the type specified, a printing wheel, means for indexing said printing wheel to printing positions, printing mechanism coöperating with said printing wheel in taking impressions therefrom and including a reciprocable frame 60 and a platen 53 carried thereon, means for holding said printing wheel in each indexed position including a ratchet 144 and a lever 145, means under the control of said reciprocable frame controlling said lever and including an arm 150 mounted on rock-shaft 151 and a cam-lever 152, and means engaging said platen and holding it out of contact with the type on the printing wheel during the descending movement of said platen.

10. In a machine of the type specified, a printing wheel, means for indexing said printing wheel, means for holding said printing wheel in each indexed position including a ratchet and a lever, an oscillating arm adapted to lock said lever, a slotted cam adapted to operate said arm, printing mechanism coöperating with said printing wheel in taking impressions therefrom and including a platen, tilting supports in which said platen is journaled, a reciprocable frame upon which said platen and its supports are mounted, a pin carried by said reciprocable frame and coöperating with said slotted cam, a latch mounted in the path of one of the platen supports and adapted to engage the same upon each descending movement of the platen to move said platen away from contact with the type wheel.

11. In a machine of the type specified, a printing wheel, printing mechanism coöperating therewith adapted to print on a web of paper and including a platen and a reciprocable frame upon which said platen is mounted, a knife adapted to sever the printed portions from said web of paper, a lever engaged by said printing mechanism at one end of the movement thereof to raise said knife, a latch adapted to hold said knife in its raised position, said latch being released by the printing mechanism at the end of the other movement of said printing mechanism.

12. In a machine of the type specified, a printing wheel, printing mechanism coöper-

ating with said wheel to print on a web of paper and including a reciprocable frame 60, platen 53, projection 106 and arm 111 carried on said frame, a spring-actuated knife 96 adapted to sever the printed portions of said web of paper, a lever 105 engaged by said projection 106 at one end of its movement to raise said knife, a latch 107 adapted to be engaged by the arm 111 when the frame 60 is in its lowermost position to release the knife 96 in its cutting operation.

13. In a machine of the type specified, printing mechanism adapted to print on a web of paper, severing means for said web, a crank adapted to set said severing means, a shaft upon which said crank is mounted, a second crank mounted on said shaft and adapted to be engaged directly by said printing mechanism at the end of the upward movement of said printing mechanism, a latch adapted to hold said severing means in a set position, and means carried by said printing mechanism and adapted to release directly said latch at the end of the downward movement of said printing mechanism.

14. In a machine of the type specified, printing mechanism adapted to print on a web of paper, severing means including a knife adapted to sever said web, springs adapted to actuate said knife when severing the paper, a crank adapted to actuate said knife against the tension of said springs, a latch adapted to hold said knife in an elevated position against the tension of said springs, a shaft upon which said crank is mounted, a second crank mounted on said shaft, a projection carried by said printing mechanism and adapted to engage said second crank at the end of the upward movement of said printing mechanism, and a pin carried by said printing mechanism and adapted to release said latch at the end of the downward movement of said printing mechanism.

15. In a machine of the type specified, printing mechanism adapted to print on a web of paper, severing means for said web, holding means for said paper, a crank adapted to actuate said severing means and said holding means, a latch adapted to hold said crank in a set position, said crank being set directly by said printing mechanism at the end of the upward movement of said printing mechanism and said latch being released directly by said printing mechanism at the end of the downward movement thereof.

16. In a machine of the type specified, printing mechanism adapted to print on a web of paper, severing means for said web, holding means for said paper, springs adapted to actuate said severing means and said holding means, a lever adapted to hold said severing means and said holding means in a set position, a shaft upon which said le-

- ver is mounted, a latch adapted to hold said severing means and said holding means in a set position, a second crank mounted on said shaft and adapted to be engaged directly by said printing mechanism at the end of the upward movement thereof, said printing mechanism adapted to directly release said latch at the end of its downward movement.
- 10 17. A standard provided with T-slots in the upper portion thereof, a base provided with a boss adapted to receive the upper portion of said standard, a reciprocable frame mounted above said base, an operating lever mounted in said standard, a connection between said lever and said reciprocable frame, a slidable bolt provided with lugs adapted to engage said T-slots to interlock said standard and boss, said bolt being also adapted to disconnect said connection from the reciprocable frame, a second lever adapted to actuate said bolt, and a pin adapted to lock said second lever.
- 15 18. In a machine of the type specified, duplex printing wheels adapted to print car line designations, means for individually indexing said duplex printing wheels, time and direction printing devices, means for indexing said devices, a serial number printing device, impression mechanism for said duplex printing wheels and said printing devices including a reciprocable frame 60, a platen 53 and a pin 153 carried by said platen, flexible connections between said se-
- rial number printing device and said reciprocable frame including a lever 184 having a slot receiving said pin 153.
- 20 19. In a machine of the type specified, printing members adapted to print upon tickets various data such as points of destination, time, directions, and serial number indications, impression mechanism co-operating with said printing members and including a reciprocable frame 60 and a platen 53 mounted thereon, means adapted to control the movement of said reciprocable frame including an element 36 having a pin 129 and a locking member 125 having a cam slot 128 engaged by said pin and actuated thereby.
- 25 20. In a machine of the type specified, a standard, printing devices mounted thereon including a platen mounted on tilting members and adapted to move over the face of said printing devices, a latch engaging one of said tilting members to move said platen away from the printing devices and to hold it away from the printing devices during its descending movement and through the continued engagement between said latch and said tilting members, an actuating lever for said platen, connections within said standard between said actuating lever and said platen, and means for cushioning the operations of said lever.
- 30 In testimony whereof we affix our signatures.

JOHN F. OHMER.
HARRY J. SIBLEY.
